FIG. 2.

FIG. 3.

A. W. Fowler

INVENTOR.

UNITED STATES PATENT OFFICE

164,909

COMBINATION TOOL

Alvah W. Fowler, Fort Worth, Tex., assignor to
William A. Uttz, Fort Worth, Tex.

Application March 17, 1951, Serial No. 14,530

Term of patent 14 years

(Cl. D44—29)

To all whom it may concern:

Be it known that I, Alvah W. Fowler, a citizen of the United States of America, residing at Fort Worth, in the county of Tarrant and State of Texas, have invented a new, original, and ornamental Design for a Combination Tool, of which the following is a specification, reference being had to the accompanying drawing, forming part thereof.

Figure 1 is a plan view of a combination tool, embodying my new design.

Figure 2 is a side elevation thereof.

Figure 3 is an end elevation.

I claim:

The ornamental design for a combination tool, substantially as shown.

ALVAH W. FOWLER.
